United States Patent [19]

Blackburn

[11] Patent Number: Des. 319,624

[45] Date of Patent: ** Sep. 3, 1991

[54] **IMPEDANCE ADAPTER FOR ELECTRONIC CIRCUITRY**

[75] Inventor: **Richard Blackburn, Co. Portneuf, Canada**

[73] Assignee: **Mux Lab Inc., Ville St-Laurent, Canada**

[**] Term: **14 Years**

[21] Appl. No.: **338,655**

[22] Filed: **Apr. 17, 1989**

[52] U.S. Cl. **D13/133**

[58] Field of Search **D13/133, 146, 147; D14/256; 439/344, 367, 381, 391, 460, 490, 573, 578, 620, 675**

CLAIM

The ornamental design for an impedance adapter for electronic circuitry, as shown and described.

DESCRIPTION

FIG. 1 is a left side elevational view of an impedance adapter for electronic circuitry showing my new design;

FIG. 2 is a front elevational view thereof;

FIG. 3 is a right side elevational view thereof;

FIG. 4 is a rear elevational view thereof;

FIG. 5 is a top plan view thereof;

FIG. 6 is a bottom plan view thereof.

FIG. 1

FIG. 2

FIG. 3

FIG. 4

FIG. 5

FIG. 6
